UNITED STATES PATENT OFFICE.

BENJAMIN F. CAWTHON, OF ELIZABETHTOWN, AND ANDREW J. CONNER,
OF LOUISVILLE, KENTUCKY.

IMPROVEMENT IN DRYING APPARATUS.

Specification forming part of Letters Patent No. **147,606**, dated February 17, 1874; application filed December 29, 1873.

To all whom it may concern:

Be it known that we, BENJAMIN F. CAWTHON, of Elizabethtown, in the county of Hardin and State of Kentucky, and ANDREW J. CONNER, of Louisville, in the county of Jefferson and State of Kentucky, have invented a new and useful Improvement in Drying Apparatus, of which the following is a specification:

Figure 1 is a top view of our improved apparatus, partly in horizontal section, through the line *x x*, Fig. 2. Fig. 2 is a vertical section taken through the line *y y*, Fig. 1.

Similar letters of reference indicate corresponding parts.

Our invention has for its object to furnish an improved apparatus for drying peat, lumber, brick, and other substances, which shall be simple in construction, easily manipulated and controlled, and effective in operation.

The invention will first be fully described, and then pointed out in the claim.

A is the furnace, which is made with a large fire-chamber, in the forward lower part of which is placed the grate *B* to receive the fuel. In the furnace *A*, in the rear of the grate *B*, is formed a bridge-wall, *C*, to throw the flames and other heated products of combustion upward around the coil of pipe *D*, placed in the upper part of the fire-chamber of the furnace.

The heated products of combustion pass out at the lower rear part of the furnace *A* through the pipe or flue *E*, which communicates with the smoke-stack *F*, placed in the rear of the furnace *A*. The pipe *E* is provided with a damper, *e'*, and the stack *F* with a damper, *f'*, so that the heated products of combustion may be made to pass out either through the pipe *E* or stack *F*, as may be desired. The pipe or flue *E* leads into one end of a drying-box, *G*, which is provided with a grate or bars, *H*, in its middle part, for the articles to be dried to rest upon, and which rests upon shoulders formed upon the sides of the said box. The drying-box *G* is provided with a cover, *I*, which is made in parts or sections, which have downwardly-projecting flanges formed upon their side and end

edges to enter grooves in the top of the said box, to keep the covers in place, and to cause them to fit closely. The covers *I* are provided with handles to enable them to be conveniently removed and replaced, as required.

The heated products of combustion pass around and between the articles to be dried, and, finally, pass out through the pipe or flue *J* into the stack or chimney *K*, which should be sufficiently high to insure a strong draft. *L* is a pipe leading from a fan-blower, and connected with one end of the coiled pipe *D*. The other end of the coiled pipe *D* is connected with a pipe, *M*, of any desired length, and which is connected with one or more drying-boxes, *N*, by branch pipes *O*, so that the heated air from the coil *D* may be introduced into said drying-boxes. The drying-boxes *N* are made exactly like the drying-box *G*, and are provided with grates and sectional covers in the same way.

The heated air, after circulating around and between the articles to be dried, escapes at the rear ends of said boxes through pipes or flues *P*. The pipes *L* and *M* are connected by a branch pipe, *Q*, which is provided with a damper, *q'*. The pipe *M* is provided with a damper, *m'*, between the end of the pipe *Q* and the coil *D*, and with a damper, *m''*, beyond each branch pipe *O*. Each branch pipe *O* is also provided with a damper, *o'*. By this construction, by closing the damper *q'*, and opening the dampers *m'* *m''* *o'*, the heated air from the coil *D* may be forced through all the boxes *N*. By closing any of the dampers *o'*, the hot air may be excluded from any of the boxes *N*. By closing the damper *m'*, opening the damper *q'*, and adjusting the dampers *m''* *o'*, cold air may be forced into any of the boxes *N*.

In using the apparatus, when one or more of the boxes *N* have been filled, hot air is forced through them until their contents are thoroughly dried, after which the dampers are adjusted, and cold air is forced through them until their contents have been sufficiently cooled to be removed. The dampers are then adjusted to shut off the air from the said boxes, and to force hot air through the boxes whose

contents have not been dried, so that the operations of drying and refilling may be going on constantly.

Having thus described our invention, we claim as new and desire to secure by Letters Patent—

The combination, with two drying-chambers, G N, and a single furnace, A B C, of air-pipes D, connected by intervening pipes with drying-chamber N, and the pipe E, carrying the products of combustion to the drying-chamber

G, as described, so that the heat evolved may be partially absorbed from the products of combustion, and its intensity lessened before being carried into chamber G, while the absorbed heat is transferred to, and utilized in, another drying-chamber.
